UNITED STATES PATENT OFFICE.

JAMES M. CONNEL AND JOHN CONNEL, OF NEWARK, OHIO.

MACHINE FOR BLACKING BOOTS, SHOES, &c.

Specification of Letters Patent No. 19,075, dated January 12, 1858.

To all whom it may concern:

Be it known that we, J. M. CONNEL and J. CONNEL, of Newark, in the county of Licking and State of Ohio, have invented
5 a new and useful Apparatus for Cleaning, Blacking, and Polishing Boots and Shoes; and we do hereby declare that the following is a full, clear, and exact description of the construction and operation of the same, reference being had to the annexed drawing, forming part of this specification, in which

Figure 1 is a top view of the apparatus. Fig. 2 is a side elevation of same, and Fig. 3 is a view showing adjustment of blacking box.

Similar characters of reference in the several figures denote the same part.

The nature of our invention consists in a shaft on which is mounted, cleaning, blacking, and polishing brush wheels, and an adjustable blacking box for the supply of the blacking wheels, the details of construction and operation being as follows:

In the drawing A is a bench serving as a seat for the operator.

B is the shaft, having its bearings in standards *a b*, and rotated by power applied to treadle C, through crank D and connecting rod D'. On this shaft are the 30 brush wheels W, W' W''. Upon the stand-

ard *a* is a semi-circular box *E*, capable of sliding thereon, when moved by means of screw *F*, as shown in Fig. 3.

The box E is adjusted so that brush W' when revolving will be supplied with blacking. The boot is held against wheel W which removes the dirt. It is then applied to wheel W' which coats it with blacking. The friction of brush W'' performs the polishing. As the blacking in box E is consumed the box is elevated by screw F.

We do not claim rotary brushes as polishers broadly considered as such is not new. But

What we do claim and desire to secure 45
by Letters Patent is—

The arrangement upon a rotary shaft of cleaning blacking and polishing brushes W W' W'' as described when combined with the vertically adjustable blacking box E 50 under the brush W' as and for the purposes hereinbefore set forth.

In testimony whereof, we have hereunto signed our names before two subscribing witnesses.

J. M. CONNEL.
JOHN CONNEL.
